UNITED STATES PATENT OFFICE.

CLIFFORD G. KING, OF PROVIDENCE, RHODE ISLAND.

COLLAPSIBLE TUBE.

1,346,897.

Specification of Letters Patent. Patented July 20, 1920.

Application filed February 20, 1920. Serial No. 360,203.

To all whom it may concern:

Be it known that I, CLIFFORD G. KING, a citizen of the United States, and a resident of Providence, in the county of Providence and State of Rhode Island, have invented a new and useful Improvement in Collapsible Tubes, of which the following is a specification.

My invention relates to collapsible tubes 10 of the type designed for dispensing tooth paste, shaving cream, library paste and the like, and the general object of my invention is to provide a simple and effective sanitary closure for the same whereby the contents of 15 the tube will be prevented from being contaminated by dirt or accumulations adjacent the nozzle thereof and from being discolored by chemical action between itself and the nozzle. A further object of my invention is 20 to provide a removable closure whereby the contents of the tube may, at the option of the user, be delivered in a flat ribbon or in cylindrical form.

My invention will be disclosed by reference 25 to the accompanying drawings in which—

Figure 1 is an elevation of a collapsible tube provided with my improved closure, the 30 slideable cap being shown in closed position. Fig. 2 is a similar view showing the slideable cap in delivery position. Fig. 3 is a fragmentary sectional view of my improved closure. Fig. 4 is an elevation on an enlarged scale of the slideable cap. Fig. 5 is a 35 longitudinal section taken on the line 5—5 of Fig. 4.

In the particular drawings selected for 40 more fully disclosing the principle of my invention 10 is a tube of tin or other flexible metal provided with the usual exteriorly threaded nozzle 11 arranged to be closed by the threaded cap 11'. The interior of the nozzle is made of non-corrosive metal, and this may conveniently be done by inserting 45 therein a non-corrosive bushing 11" and swaging the ends thereof over the ends of the nozzle. Located within said bushing is a removable longitudinally-slidable cap 12 having a flanged head 13 arranged to abut 50 the end of the nozzle when said slideable cap is in closed position as shown in Figs. 1 and 3. The cap 12 is provided with a side delivery-opening 14 which when said cap 55 is in closed position is preferably even with the top of the tube and when it is in delivery

position projects slightly beyond the end of the nozzle 11.

Preferably the inner end of the cap 12 is provided with small projections 15 arranged to contact with the inner surface of the 60 nozzle and prevent the removal of the cap by the pressure of the paste. The inner end of the cap preferably is slotted in several places as shown at 16 to give a certain elasticity to the body of said cap, so that 65 the user by grasping the head 13 may readily draw the cap out of the nozzle.

The bushing 11" must be made of metal 70 that is sufficiently hard to prevent the projections 15 from grooving the same and thereby permitting the paste to leak through the nozzle, there being at all times a perfect fit between the cap 12 and said bushing.

It will be obvious that by squeezing the 75 end of the tube between the thumb and forefinger as indicated in Fig. 2, the pressure thereby exerted on the paste will force the cap 12 outwardly and the paste will be delivered through the opening 14 in the form of a flat ribbon as indicated at 16. By removing the cap 12 the paste may be discharged through the nozzle in the form of a 80 cylinder in the usual manner.

The slideable cap 12 preferably is made 85 of nickel alloy or some metal which will not be oxidized by the contents of the tube.

It will be apparent that by means of my 90 improved closure the parts of the tube adjacent to the delivery opening cannot contaminate the paste as it discharges therefrom inasmuch as immediately after a portion of the paste has been forced from the tube, the cap 12 will be pushed back into closed position and it will be apparent also that the closure is complete and therefore 95 that my tube is particularly adapted for pastes which become hardened upon exposure to the air.

Having thus described an illustrative embodiment of my invention without however 100 limiting myself thereto what I claim and desire to secure by Letters Patent is:

1. A collapsible tube, comprising a nozzle, a longitudinally-slidable cap located in said nozzle, said cap having a side delivery-opening and a flanged head, and a cap threaded to said nozzle and arranged to lock the slideable cap in closed position. 105

2. A collapsible tube, comprising a nozzle, a removable longitudinally-slidable cap in 110

- said nozzle, said cap having a side delivery-opening and a flanged head, and a cap threaded to said nozzle and arranged to lock the slidable cap in closed position.
5. 3. A collapsible tube, comprising a nozzle, a removable longitudinally-slidable cap in said nozzle, said cap having a side delivery-opening and a flanged head, the inner end of said cap being slotted and provided with 10 projections arranged to engage the inner surface of said nozzle, and a cap threaded to said nozzle and arranged to lock the slidable cap in closed position.
4. A collapsible tube, comprising a nozzle, 15 the interior surface of which is of relatively hard, non-corrosive metal, a removable longitudinally-slidable cap in said nozzle, said cap having a side delivery-opening and a
- flanged head, and a cap threaded to said nozzle and arranged to lock the slidable cap 20 in closed position.
5. A collapsible tube, comprising a nozzle, a bushing of relatively hard, non-corrosive metal in said nozzle, a removable longitudinally-slidable cap in said nozzle, said cap having a side delivery-opening and a flanged head, and a cap threaded to said nozzle and arranged to lock the slidable cap 25 in closed position.
- In testimony whereof, I have hereunto 30 subscribed my name this 17th day of February, 1920.

CLIFFORD G. KING.

Witness:

DANIEL H. MORRISSEY.
